UNITED STATES PATENT OFFICE.

EDWARD CLIFF, OF NEWARK, NEW JERSEY.

HOSE-REEL.

SPECIFICATION forming part of Letters Patent No. 601,632, dated April 5, 1898.

Application filed October 18, 1897. Serial No. 655,546. (No model.)

To all whom it may concern:

Be it known that I, EDWARD CLIFF, a citizen of the United States, and a resident of Newark, in the county of Essex and State of New Jersey, have invented certain new and useful Improvements in Hose-Reels, of which the following is a specification.

The invention relates to improvements in hose-reels, and particularly to improvements in hose-reels of the character employed in buildings having a fixed water-supply apparatus to which the hose may be permanently applied.

In the embodiment of my invention herein presented the reel proper is keyed upon the stem of the valve controlling the flow of water, and said valve is opened by the unwinding of the hose from the reel, so that upon the hose being unwound for use the water is automatically turned on and is within the hose as soon as the latter can be used. When fully unwound, the hose is entirely free of the reel and is simply left connected with the exposed water-supply apparatus. After the use of the hose in extinguishing a fire the reverse motion of the reel, without regard to the hose, will close the valve in the water-supply pipe, and thereafter at any convenient time by unkeying the reel from the valve-stem, but leaving said reel to turn freely on said stem or on a sleeve around said stem, the hose may be rapidly rewound upon the reel without affecting the valve.

The invention will be fully understood from the detailed description hereinafter presented, reference being had to the accompanying drawings, in which—

Figure 1 is a central vertical longitudinal section through a reel and water-supply apparatus embodying the invention, the valve controlling the flow of water being shown in its closed position and the hose being omitted from the water-supply pipe. Fig. 2 is a side elevation, partly broken away, of a reel and hose embracing the invention; and Fig. 3 is an enlarged detached side elevation of a portion of the reel.

In the drawings, A designates the reel, which is composed of the hub B and plates or disks C C, the latter being secured to the flanges D of said hub by means of the bolts E, upon

which the hose F is wound, as indicated more clearly in Fig. 2.

The hub B is of cast metal and contains the circular hollow bore G to receive the sleeve H, which incloses the valve-stem I and is connected with the valve-casing J, the latter being supported upon the water-supply pipe K. The hub B is cast with the radial end flanges D and with the webs L, which connect said flanges within the line of the bolts E, as indicated in Fig. 1. The plates or disks C C have central apertures, as shown, the disk nearest to the valve-casing J having its central aperture of the same size as the bore G of said hub B, while the disk C at the outer side of the reel has its central aperture of smaller diameter than the bore G of said hub B, whereby a portion (lettered M) of said disk projects inward and forms an annular flange 70 or lip which is utilized, as hereinafter described, for fastening the reel A and valve-stem I together, so that the movement of the reel turning on its axis will effect the longitudinal movement of the valve-stem I. 75

The valve-casing J, the water-pipe K, and the valve N are of well-known form, said valve-casing, as usual, receiving the sleeve H and being provided with the nozzle O, to which the hose F is attached. The sleeve H is internally threaded to engage the thread on the valve-stem I, which, as clearly illustrated in Fig. 1, carries the valve N and is threaded in part and left of polygonal form in cross-section in part. The threaded portion of the valve-stem I engages the internal thread of the sleeve H, and thus when the valve-stem is rotated by means of the reel or otherwise the said valve-stem is caused to have a reciprocating motion, causing the valve M to engage its seat or to recede therefrom. The hub B of the reel turns freely upon the exterior surfaces of the sleeve H, but is keyed thereon, so as not to travel longitudinally upon said sleeve. The keys 90 securing the hub B to the sleeve H are illustrated by dotted lines in Fig. 3 and in section in Fig. 1, and they are lettered P, and said keys are simply in the form of round pins carried by the hub B and entering the annular groove Q, which is formed in said sleeve H. The keys P are in effect rigid with the

hub B, and their inner surfaces rest within the annular groove Q of the sleeve H, and thus the reel A may have a free axial motion around the sleeve H, but will be prevented 5 from traveling longitudinally on said sleeve by means of the keys P. The keys P are simply convenient forms of keys, and the present invention is not confined to any special means for keying the hub B upon the 10 sleeve H.

Upon the outer portion of the valve-stem is applied the externally-threaded sleeve R, having a polygonal central bore loosely fitting upon the polygonal portion of the valve- 15 stem I. The sleeve R is externally threaded to receive the nut S and jam-nut T, and at its inner end is formed with the head V, which is within the bore G of the hub A and at the inner side of the outer disk C, as clearly 20 shown in Fig. 1. The sleeve R is passed upon the valve-stem I until the head V of said sleeve is within the bore G of the hub B before the outer disk C is secured in place, and thus the head V comes at the inner side of 25 said outer disk C, and the inwardly-projecting portion M of said disk is between the said head V and the securing-nut S. It will be apparent from an inspection of Fig. 1 that when the nut S is screwed firmly home the 30 inwardly-projecting portion M of the outer disk C will be rigidly secured between said head and said nut and that thereby the reel A, while free to revolve upon the sleeve H, is rendered rigid with the sleeve R, which is in- 35 capable of rotation except with the valve- stem I. The loosening of the nut S from the inwardly-projecting portion M of the outer disk C leaves the reel A free to rotate upon the sleeve H without affecting the sleeve R 40 or valve-stem I.

The hose F is at one end provided with the usual nozzle W and at its other end is coupled to the nozzle O, forming a part of the permanent water-supply apparatus. The end of the 45 hose F which is coupled to the nozzle O, as indicated in the drawings, while removable, is not intended to be removed from said nozzle except on some occasion in which it might be desired to examine the valve or make other 50 inspection. In winding the hose upon the reel, one end of the hose being coupled to the nozzle O, the hose at about its center will be folded upon a cylinder or core of the kind shown in Letters Patent of the United States, 55 No. 585,861, granted to me July 6, 1897, and the said cylinder or core (indicated in Fig. 2 by the letter X) will be placed within one of the spaces between the webs L of the hub B, and thereupon the hose will be wound 60 upon the bolts E in double layers, the discharge-nozzle W being left in close proximity to the reel A. The hose F will preferably be wound upon the reel A when the latter is upon the sleeve H and the nut S is loosened from 65 the outer disk C, in which condition the reel A is free to be revolved in either direction without affecting the valve-stem I. The hose

being wound upon the reel A, the latter will be secured to the valve-stem I by the tightening of the nut S against the inwardly-projecting portion M of the outer disk C, and upon this being done the reel may be left until occasion shall arise requiring its use. 70

In the employment of the apparatus for the extinguishing of a fire the attendant will seize 75 the nozzle W and carry the same toward the fire, this action of pulling on the hose causing the reel to unwind the latter and at the same time to effect the outward movement of the valve-stem I and valve N, whereby the 80 water from the pipe K may pass through the nozzle O into the hose F. The hose will be drawn from the reel until all of the hose has been released therefrom and is left hanging from the nozzle O free of the reel. After the 85 fire has been extinguished the valve N, without regard to the hose, will be closed by causing a reverse rotation of the reel A upon the 90 sleeve H, and after the valve N has been closed the hose F may be restored to the reel A. In 95 restoring the hose to the reel A it will first be necessary to loosen the nut S from the outer disk C, and thereupon the hose at about its center will be doubled upon itself, as before, and placed upon the reel A, which, being then 100 free of the nut S, may be conveniently revolved to wind the hose upon itself without affecting the valve-stem I or valve N. After the hose has been again fully wound upon the reel A the nut S will be retightened against the disk 105 C, and thus the reel is again in condition and position for immediate use. The nut S locks 110 a part of the reel A to the sleeve R, and the latter is keyed upon the valve-stem I, and thus when the nut S is tightened against the disk 105 C the sleeve R and reel A will revolve together and cause the thread on the valve-stem to travel in the thread within the bore of the sleeve H, the effect being that the valve-stem will have a longitudinal movement and pass 115 through the sleeve R.

The reel made the subject of this application is shown upon a horizontal sleeve H and valve-stem I; but the invention is not limited to the position the reel may occupy with respect to the wall adjacent to which it may be placed, and said reel, sleeve H, and valve- 120 stem I may, when desired, be placed in a vertical position or arranged at an angle of forty-five degrees or at any other angle which may 125 be found convenient under conditions to be met in supplying the apparatus to buildings.

The sleeve R is directly on and carried by the valve-stem, and thus the means for connecting the reel with the valve-stem are 130 wholly independent of the reel.

What I claim as my invention, and desire to secure by Letters Patent, is—

1. In combination with the water-supply apparatus having the valve, projecting valve- 130 stem and exposed hose-attaching nozzle, the reel adapted to operate said stem, means connecting the reel with said stem but permitting said stem to move longitudinally, means re-

straining said reel, while revolving, against traveling with said stem, and the hose at one end connected with said exposed nozzle and thence while doubled at about its center 5 wound upon said reel; substantially as set forth.

2. In combination with the water-supply apparatus having the valve, valve-stem and exposed hose-attaching nozzle, the sleeve 10 around said stem, the reel mounted on said sleeve, means for preventing the reel while revolving from traveling longitudinally on said sleeve, means connecting said reel with said stem to transmit the motion of the reel 15 to said stem to operate the valve, and the hose at one end connected with said exposed nozzle and thence while doubled at about its center wound upon said reel; substantially as set forth.

20 3. In combination with the water-supply apparatus having the valve, projecting valve-stem, and exposed hose-attaching nozzle, the sleeve connected with said water-supply apparatus and having an internal thread, the 25 reel mounted upon said sleeve, means connecting a polygonal portion of said valve-stem with said reel but permitting said stem during the revolving of the reel to travel longitudinally, means preventing said reel 30 from having a traveling motion while revolving on said sleeve, and the hose at one end connected with said exposed nozzle and thence wound upon said reel; substantially as set forth.

35 4. The water-supply apparatus having a hollow sleeve, a valve and a valve-stem projecting through said sleeve, combined with a reel mounted to turn axially upon said sleeve, the sleeve R, having a polygonal aperture fitting upon a polygonal portion of said valve-stem and provided at one end with a head and at its other end with a nut, whereby said sleeve may be clamped against a portion of said reel to connect the reel and valve-stem, 40 and suitable hose wound upon said reel; substantially as set forth.

5. In combination with the water-supply apparatus having a sleeve, a valve and a valve-stem projecting into said sleeve and having 50 a threaded portion to engage the thread of said sleeve and also a polygonal portion, the reel mounted to revolve upon said sleeve and

otherwise stationary therewith, the sleeve R having a polygonal aperture receiving the polygonal portion of said valve-stem and 55 having also the head G within the bore of said reel, the nut S on said sleeve R for clamping a portion of said reel against said head, and hose suitably wound upon said reel; substantially as set forth.

6. In combination with water-supply apparatus having the internally-threaded sleeve, the valve and the valve-stem projecting into said sleeve and being threaded in one portion and polygonal in cross-section in another 65 portion, the reel mounted to revolve upon said sleeve and keyed thereon and extending outward beyond the outer end of said sleeve, the sleeve R having a polygonal aperture receiving said valve-stem and provided with 70 the head G intermediate the outer end of said sleeve and the outer portion of the reel, and the nut upon said sleeve R to clamp said outer portion of the reel against the said head G; substantially as set forth.

7. In combination with water-supply apparatus having a valve, a sleeve and a valve-stem projecting through said sleeve, the reel receiving within its hub said sleeve and valve-stem, means directly on and carried by said 80 valve-stem for detachably connecting said stem with said reel so that said stem may receive the motion of said reel, and means for preventing said reel from traveling longitudinally with said stem; substantially as set 85 forth.

8. In combination with water-supply apparatus having a sleeve, a valve and a valve-stem projecting through said sleeve, the reel mounted upon said sleeve, a key securing 90 said reel upon said sleeve but permitting of the revolving motion of said reel around said sleeve, the sleeve R upon and carried by a polygonal portion of said valve-stem, and means for connecting the said sleeve R to the 95 reel; substantially as set forth.

Signed at New York, in the county of New York and State of New York, this 15th day of October, A. D. 1897.

EDWARD CLIFF.
